UNITED STATES PATENT OFFICE.

LOUIS GOHLKE, OF GRAND RAPIDS, MICHIGAN, ASSIGNOR TO T. STEWART WHITE, THOMAS FRIANT, GAIUS W. PERKINS AND CHARLES J. REED.

DESIGN FOR A CASING FOR CARPET-SWEEPERS.

SPECIFICATION forming part of Design No. 24,884, dated November 12, 1895.

Application filed October 14, 1895. Serial No. 365,694. Term of patent 7 years.

To all whom it may concern:

Be it known that I, LOUIS GOHLKE, a citizen of the United States, residing at Grand Rapids, in the county of Kent and State of Michigan, have invented a certain new and original Design for Carpet-Sweeper Casings, of which the following is a specification.

This design relates to a carpet-sweeper casing, and the distinctive features thereof are the longitudinally-rectilinear top of the case having a central transversely-curved panel and a concave-inclined panel at each side thereof having upwardly and outwardly-projecting rounded edges, as more fully illustrated in the accompanying drawings, in which—

Figure 1 is an end elevation of a carpet-sweeper casing embodying said design, and Fig. 2 a plan view of the same.

Like letters refer to like parts in both of the figures.

A represents the central panel which is substantially convex, being only slightly concave near its sides, as at A' A'.

B B represent the side panels, parallel to 25 and at each side of the middle panel A and overlapping the same, said side panels being inclined downward and outward at about twenty-five degrees from the horizontal and having upwardly and inwardly projecting 30 rounded or beaded edges B' adjacent to the edges of the panel A', and outwardly-projecting rounded edges B'' at the upper angles of the case, and concave central portions B, the inner edge of each of said panels being thicker 35 than the outer edge of the same. All of said panels are longitudinally rectilinear, substantially as shown.

What I claim is—

The design for a carpet-sweeper casing substantially as shown, and described.

In testimony whereof I affix my signature in the presence of two witnesses.

LOUIS GOHLKE.
